(57) **CLAIM**

The ornamental design for a body hair trimmer as shown and described.

DESCRIPTION

FIG. 1 is a front, left and top perspective view of a body hair trimmer, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, left and top perspective view of the body hair trimmer of FIG. 1 shown in an environment of use. The dashed broken lines depict portions of the body hair trimmer that form no part of the claimed design. The additional dashed broken lines in FIG. 9 depict environmental structure and form no part of the claimed design.

1 Claim, 9 Drawing Sheets
